CLAIM

The ornamental design for a vehicle wheel spoke, as shown and described.

DESCRIPTION

FIG. 1 is a front perspective view of a vehicle wheel spoke showing my new design;

FIG. 2 is another front perspective view thereof; and,

FIG. 3 is a front view thereof.

The broken lines show portions of the vehicle wheel spoke which form no part of the claimed design. The dash-dot-dash line(s) define the bounds of the vehicle wheel spoke and form no part thereof.
